UNITED STATES PATENT OFFICE.

LESLIE B. GRAHAM, OF EAST CHICAGO, INDIANA, ASSIGNOR TO NATIONAL BOILER WASHING CO., OF CHICAGO, ILLINOIS, A CORPORATION OF ILLINOIS.

OIL-SERVICE STANDPIPE.

Application filed March 1, 1920. Serial No. 362,385.

To all whom it may concern:

Be it known that I, LESLIE B. GRAHAM, a citizen of the United States, residing at East Chicago, in the county of Lake and State of Indiana, have invented certain new and useful Improvements in Oil-Service Standpipes, of which the following is a specification.

This invention relates to a stand pipe through which to deliver oil, and which is equipped with a delivery spout which is normally withdrawn from delivery position, but which may be manipulated to present it in delivery position when needed.

One object of the invention is to provide a novel construction of delivery spout which will be adapted to conserve drippings of the liquid to be delivered, and so avoid waste after the spout is withdrawn from the container (for instance the tender of a locomotive) to which the liquid is to be delivered.

A further object of the invention is to utilize the drip-container as a counterpoise for automatically withdrawing the spout from delivery position, or maintaining it in its withdrawn position. Subordinate objects of the invention are to provide details of construction of the several elements of the device whereby it will be adapted to effectively serve the purposes for which it is intended.

In the accompanying drawings—

Figure 1 is an elevation of an apparatus embodying the several features of the present invention, and shown in position to deliver liquid, for instance, fuel oil, to the tender of a locomotive, the retracted position of the spout being shown in dotted lines.

Figure 2 is an elevation of the device shown in Figure 1 but viewed in a direction at right angles to the view of Figure 1.

Figures 3 and 4 are two views on an enlarged scale of the hanger which supports the trunnioning sling in which the spout is mounted.

Figure 5 is a detailed assembly view of the discharge end of the delivery pipe with the hanger and sling mounted thereon, and a portion of the spout lying in the sling; and

Figure 6 is a view of the parts shown in Figure 5 but viewed in a direction at right angles to that of Figure 5.

1 represents a stand pipe having a down-

wardly presented delivery end or bib 2, and 3 represents a spout which is trunnioned at 4 in order that it may move from the full line position of Figures 1 and 2, in which it is adapted to direct liquid to a container to be discharged (for instance, the fuel tender of an oil-burning locomotive), to the dotted line position of Figure 1 in which it remains until called into use.

Spout 3 has a receiving box 5 which is presented in relation to the discharge end 2 to receive the liquid from the latter and confine and direct the liquid to the spout. In the use of a device of this kind, and particularly when the stand pipe is used for delivering oil, it is very desirable to avoid the drip which usually follows the removal of the spout, and to conserve the film of oil which adheres to the wall of the spout after it is withdrawn from delivery position. To this end, the present invention provides a box with a hollow extension 5^a having tight walls, which constitutes a drip receptacle or cup, see particularly Figure 5, into which the residual liquid may run when the spout resumes vertical position. The extension 5^a may serve the additional purpose of a counterpoise for the spout 3 to hold the latter in retracted or vertical position, as suggested in dotted lines in Figure 1, a heavy cast iron or other cap 5^b being added if necessary to render the counterbalance effective.

In order to mount the spout 3 upon the stand pipe, a hanger 6 with a sleeve 7 is fitted around the bib 2 and held thereon by any suitable form of shoulder, such, for instance, as may be conveniently provided by the coupling sleeve 8 threaded on the lower end of the bib 2, and this hanger is provided with a pair of spaced arms 9 that receive the trunnions 4 already referred to. For securing the spout 3 on the trunnions 4 a sling 10 is provided which is connected by the trunnions with the arms 9, and in which sling the spout 3 is laid and secured.

The sleeve 7 swivels upon the bib 2 so that the spout may swing to present its delivery end to either one of two tracks between which the stand pipe is located, the extension 5^a passing between the depending bib and the stand pipe in this swinging movement, as suggested by dotted lines in Figure 2. Obviously, the horizontal offset between the depending bib 2 and the stand

pipe 1 may be of any desired length since its position will be parallel to the tracks. This in turn admits of any desired length of extension 5^a beyond the trunnions 4.

5 11 represents the usual valve, and 12 the flexible connections for controlling the same. 13 represents a flexible connection which may be used for drawing down the spout from retracted to delivery position.

10 14 represents a steam pipe located within the stand pipe 1 and terminating in a choked discharge nozzle 14^a which permits a sufficient escape of steam to keep up circulation through the steam pipe. In this way the 15 temperature of the oil in the stand pipe may be kept up, and the oil prevented from taking on a viscous consistency which would greatly interfere with its discharge when the valve is opened.

20 I claim:

1. In combination with a supply pipe for the delivery of fluid, a tilting discharge spout adapted to assume a delivery position to deliver fluid from the supply pipe and also a retracted position, and having a drip receptacle adapted to confine the fluid remaining after the spout is retracted, said receptacle being located at the end of said spout opposite to the delivery end thereof.

25 2. In combination with a supply pipe for the delivery of fluid, a discharge spout adapted to assume a delivery position to deliver fluid from the supply pipe and also a retracted position, and having a drip receptacle adapted to confine the fluid remaining after the spout is retracted; said receptacle comprising an extension of the spout located on the opposite side of the receiving point from the delivery end of the 40 spout.

3. In combination with a supply pipe for fluids, a pivotally mounted delivery spout adapted to assume delivery position and also retracted position with relation 45 to the supply pipe, and having a receptacle for residual fluid located on the opposite side of its pivot from its delivery end.

4. A delivery spout for fluids having one end constructed to discharge fluid and its other end constructed to provide a drip receptacle; said discharge spout being pivoted intermediately of its said ends and adapted to swing upon its pivot to assume a position with its discharge end depressed, also a position with its discharge end elevated and the drip receptacle in position to collect fluid remaining in the spout after elevation.

5. A delivery spout for fluids having one end constructed to discharge fluid and its other end constructed to provide a drip receptacle; said discharge spout being pivoted intermediately of its said ends and adapted 60 to swing upon its pivot to assume a position with its discharge end depressed

also a position with its discharge end elevated and the drip receptacle in position to collect fluid remaining in the spout after elevation; said drip receptacle being positioned to discharge into the spout when the latter is in its depressed or delivery position.

6. A delivery spout for fluids having one end constructed to discharge fluid and its other end constructed to provide a drip receptacle; said discharge spout being pivoted intermediately of its said ends and adapted to swing upon its pivot to assume a position with its discharge end depressed, also a position with its discharge end elevated and the drip receptacle in position to collect fluid remaining in the spout after elevation; said drip receptacle acting upon the spout in the direction to elevate its delivery end.

7. A delivery spout for fluids having one end constructed to discharge fluid and its other end constructed to provide a drip receptacle; said discharge spout being pivoted intermediately of its said ends and adapted to swing upon its pivot to assume a position with its discharge end depressed, also a position with its discharge end elevated and the drip receptacle in position to collect fluid remaining in the spout after elevation; said drip receptacle being adapted to 90 counter-balance the delivery end and maintain it in elevated position.

8. In combination with a delivery pipe for liquids, a delivery spout, and a drip receptacle; said spout being movable from 100 a depressed or delivery position to an elevated or flow-arresting position; and said drip receptacle assuming a position to discharge into the spout when the latter is depressed and to receive liquid from the spout 105 when the latter is elevated.

9. In combination with a delivery pipe for liquids a delivery spout, and a drip receptacle; said spout being movable from a 110 depressed or delivery position to an elevated or flow-arresting position; said drip receptacle assuming a position to discharge into the spout when the latter is depressed and to receive liquid from the spout when the latter is elevated; and said spout and drip receptacle being rigidly united and being mounted upon a common pivot.

10. The combination of a delivery pipe having a discharge end, and a delivery spout and drip receptacle movably mounted 120 in relation to said discharge end; said spout and drip receptacle being tiltable to present them alternately into receiving relation to said discharge end.

11. In combination with a delivery pipe having a downwardly presented discharge end, a hanger comprising a sleeve surrounding said discharge end and rotatable thereon, with arms depending below the sleeve, and a tiltable discharge spout trunnioned 125 130

on said depending arms adapted to swing by the rotation of the sleeve to different delivery positions, said spout having a drip receptacle at the end thereof opposite to the discharge end of said spout.

12. In combination with a delivery pipe having a depending discharge end, a sleeve rotatably mounted on said discharge end and having a pair of depending arms, a sling trunnioned on said depending arms, and a tiltable discharge spout resting on said sling and rotatable with the sling and sleeve to present the discharge spout in different delivery positions, said spout having

a drip receptacle at the end thereof opposite to the discharge end of said spout.

13. The combination of a delivery pipe having a discharge end portion, a tiltable spout, and a rotatable member mounted on said end portion for tiltably supporting said spout, whereby said spout may have a universal movement, said spout having a drip receptacle at the end thereof opposite to the discharge end of said spout.

Signed at Chicago, Illinois, this 20th day 25 of February, 1920.

LESLIE B. GRAHAM.
